US00D521505S

(12) **United States Design Patent** (10) Patent No.: **US D521,505 S**
Shively et al. (45) Date of Patent: **** May 23, 2006**

(54) **SET OF BUTTONS FOR OPERATING AN ELECTRICAL DEVICE**

(75) Inventors: **Orrin J Shively**, Glendale, CA (US); **Andy M Ogden**, Pasadena, CA (US)

(73) Assignee: **Disney Enterprises, Inc.**, Burbank, CA (US)

(**) Term: **14 Years**

(21) Appl. No.: **29/185,284**

(22) Filed: **Jun. 25, 2003**
